Primary Examiner — Susan Bennett Hattan*Assistant Examiner* — Brett Miller*(74) Attorney, Agent, or Firm* — Clifford H. Kraft(57) **CLAIM**

The ornamental design for beverage dispenser capsule, as shown and described.

DESCRIPTION

This application is related to the application for a “beverage dispenser capsules,” application Ser. No. 29/455,870, concurrently filed.

FIG. 1 is a top perspective view of a beverage dispenser capsule; showing my new design;

FIG. 2 is a bottom perspective view thereof;

FIG. 3 is a top plan view thereof;

FIG. 4 is a bottom plan view thereof;

FIG. 5 is a front elevational view thereof; and,

FIG. 6 is a side elevational view thereof.

The broken lines depict portions of the beverage dispenser capsule that form no part of the claimed design.
